UNITED STATES PATENT OFFICE.

FRITZ FINCKH, OF ESSEN, GERMANY, ASSIGNOR TO FRIED. KRUPP AKTIENGESELLSCHAFT, OF ESSEN-ON-THE-RUHR, GERMANY.

BARREL-RECOIL GUN.

1,394,984.

Specification of Letters Patent. Patented Oct. 25, 1921.

Original application filed September 4, 1920, Serial No. 408,376. Divided and this application filed April 26, 1921. Serial No. 464,683.

To all whom it may concern:

Be it known that I, FRITZ FINCKH, a citizen of the German Republic, and resident of Essen, Germany, have invented certain new and useful Improvements in Barrel-Recoil Guns, (for which I have filed application in Germany, filed August 22, 1918,) of which the following is a specification.

This invention relates to barrel recoil guns and the object of the invention is to enable the guns of railway guns which are to be made or already existent naval guns to be used on a naval carriage or railway carriage without important alterations being made in the gun barrels and cradles.

This application is a division of my application Serial No. 408,376 now Patent No. 1,379,543.

The various features of the invention will be more particularly described with reference to the accompanying drawings in which:

Figure 1 is a side elevation of the barrel recoil gun showing the parts pertaining to the present invention,

Fig. 2 is a view of Fig. 1 looking from the left,

Fig. 3 is a plan view of the structure shown in Fig. 1,

Fig. 4 is a side elevation partly in section of the structure illustrated in Fig. 1 but altered according to the invention,

Fig. 5 is a section on line 5—5 of Fig. 4, and,

Fig. 6 is a plan view of the structure illustrated in Fig. 4.

In the drawings the reference character A indicates a gun barrel which is carried by cradle H. Rigidly mounted on the cradle and at one end thereof is a pair of trunnions J. The cradle H also carries a member h', in which the cylinder K of a recoil brake and running gear is attached in an easily detachable manner. The corresponding piston rod k' can be attached to a horn m' on a ring M rigidly attached to the gun barrel. On the member h' an eye h² is mounted for a purpose to be hereinafter described.

When the cradle H together with the gun barrel, brake and the like is used for a naval gun, these parts are put together in the manner shown in Figs. 1 to 3. The trunnions J then lie at the end of the cradle which is next to the muzzle of the gun barrel,

and the elevating gear is attached to the eye h². If on the other hand the arrangement shown in Figs. 4 to 6 is to be built into a railway gun carriage, the cradle H is inserted in the frame of the gun carriage in a reversed position (see Figs. 4 to 6).

The end of the cradle which carries the trunnions J is then located in the vicinity of the breech of the gun barrel. In this case the easily detachable cylinder K, which is connected to the member h¹ of the cradle H, must also be reversed, so that the end of the cylinder which is provided with a stuffing box for the rod h¹ is turned toward the horn m¹ of the ring M.

Furthermore the rod h¹ is lengthened by a piece k² screwed to it and attached to the horn m¹. When the cradle H is used on a railway gun carriage, the ring M may bear against the cradle H when the gun is in the firing position, or if the distance of the trunnions J from the breech end of the gun barrel is to be increased and the preponderant weight in front of the parts oscillating about the trunnions is to be reduced, a ring N may be inserted between the rear end of the cradle H and the ring M and be attached to the cradle. The ring N is provided with a projection n¹ which carries an eye n² for the attachment of the elevating gear and has a boring n³ for the rods h¹ k². The last described arrangement is specially suited for the conversion of existing naval guns.

Having thus described my invention, what I claim is:

1. A barrel recoil gun which comprises a gun barrel, a cradle therefor, a pair of trunnions carried by said cradle, said cradle being reversible to vary the distance between the trunnions and the breech end of the gun barrel.

2. A barrel recoil gun which comprises a gun barrel, a cradle therefor, a pair of trunnions carried by said cradle, a recoil device, means on said gun barrel for connection with said recoil device, additional means on said gun barrel for enabling a gun elevating mechanism to be attached thereto, said cradle being reversible on the gun barrel for the purpose described.

The foregoing specification signed at 105 Essen, Germany, this 3rd day of March, 1921.

FRITZ FINCKH,
